UNITED STATES PATENT OFFICE.

THEODORE M. PRUDDEN, OF NEWTON, MASSACHUSETTS.

BALL-BEARING SPINDLE.

1,341,019.

Specification of Letters Patent. Patented May 25, 1920.

Application filed May 23, 1919. Serial No. 299,141.

To all whom it may concern:

Be it known that I, THEODORE M. PRUDDEN, a citizen of the United States, residing at Newton, county of Middlesex, State of Massachusetts, have invented an Improvement in Ball-Bearing Spindles, of which the following description, in connection with the accompanying drawing, is a specification, like characters on the drawing representing like parts.

This invention relates to improvements in ball-bearing spindles, and the object thereof is to provide a novel form of spindle of simple construction which will be efficient in operation and which may be easily assembled and accurately adjusted.

A further object of the invention is to provide a ball-bearing spindle having means whereby the bearings may be adjusted, and the adjustment may be sealed so that it cannot be tampered with.

A further object of the invention is to provide a novel means for sealing the lower step-bearing against improper adjustment.

25 A further object of the invention is to provide a ball-bearing spindle in which the spindle may be inserted into its casing from the top in assembling the same, and which will be prevented from removal from the casing when the lower bearing is adjusted to operative position.

30 A further object of the invention is to provide a ball-bearing spindle having a whirl which is located above the upper bearing.

35 Other objects and features of the invention will more fully appear from the following description and accompanying drawings and will be pointed out in the annexed claims.

40 A preferred embodiment of my invention is illustrated in the accompanying drawings, in which—

45 Figure 1 is a side elevation of a spindle blade, whirl, and casing or bolster for the spindle bearing.

50 Fig. 2 is a vertical, longitudinal, sectional view of the bolster, and upper and lower ball-bearings, and whirl showing the spindle blade in elevation.

55 Fig. 3 is a transverse sectional view on lines 3—3, Fig. 2 looking upwardly.

Fig. 4 is a side elevation of the lower step-bearing.

55 The spindle bearing illustrated in the ac-

companying drawing comprises a casing or bolster having a cylindrical body portion 1, the central portion of which is provided with screw threads 2, by means of which the same can be attached to the rail of the 60 spinning machine or any other suitable support. The lower portion 3 of the body may be of smaller diameter to permit it to be thrust through the screw threaded opening in a supporting means. The casing or bolster is provided with an enlarged upper end 4 having a preferably cylindrical chamber 5 for the upper ball-bearings. The lower end of the body portion of the casing or bolster is open and the walls thereof preferably are provided with screw threads 6 adapted to engage complementary threads upon the lower step-bearing 7, which preferably is in the form of a cup adapted to receive a series of balls 8, which engage the 75 lower beveled end 9 of the spindle blade 10.

The upper bearing for the spindle blade 10 preferably comprises a cone 11, which may be made integral with the spindle blade, but preferably is made separately, 80 and shrunk or otherwise secured upon a spindle blade, and a co-operating bearing member 12, which may be in the form of a cup providing a race-way 13 for a series of balls 14. The bearing member or cup 12 85 desirably is fitted within the upper portion of the cylindrical chamber 5, the outer wall 15 of said cup member having a creeping fit within the cylindrical wall 16 of the enlarged portion 4 of the casing, so that during the rotation of the spindle the cup member 12 of the bearing may be allowed gradually to rotate or creep, thereby preventing wear upon only one side of the bearing, which would occur if the cup member were 90 retained rigidly in one position. The wall 15 of the cup member may be provided with one or more recesses 17 adapted to catch and retain dust which may creep down between said wall and the wall 16 of the 100 casing.

In order to retain the cup member 12 of the upper bearing in the chamber 5, the wall 16 is provided with an annular groove 18 near its top adapted to receive an expanding 105 locking member, which desirably is in the form of a resilient ring 19. The upper portion of the cup member 12 desirably is provided with a beveled or grooved face 20 adapted to engage the ring 19 and secure it 110

in the groove 18, thereby positively locking the bearing against removal. The depth of the chamber 5 is, of course, such that when it is desired to remove the spindle from the casing the step-bearing 7 must be retracted sufficiently to release the engagement of the beveled portion 20 of the cup bearing from contact with the ring 19, whereupon the ring 19 may be pried out of the groove 18 by 10 a suitable instrument.

The construction of the upper bearing, above described, is such that when the cup 12 is locked against the ring 19 and the step-bearing 7 properly adjusted in respect to 15 the lower end of the spindle blade, there can be no play which will interfere with the proper operation of the spindle.

Inasmuch as tampering with the adjustment of the ball-bearing spindles results in 20 throwing the spindle out of proper alignment and destroying their effectiveness means have been provided whereby the manufacturer or person setting up the spindle may seal the bearings. A convenient 25 means, which is illustrated herein, is provided by cutting a groove transversely of the lower end of the step-bearing, the walls of the groove or slot 21 preferably being undercut, as illustrated in Fig. 4, so that the 30 slot will serve to support a suitable sealing material. This groove may be conveniently formed by boring a hole transversely of the lower portion of the step-bearing, then surfacing off the lower portion of the bearing 35 until it breaks into the hole thus bored.

In assembling a spindle bearing above described the spindle may be inserted through the central aperture in the cup member 12, and the balls 14 introduced between said 40 cup member and the cone 11, and the whirl 22 may be secured to the spindle blade. The cup member will then be inserted in the chamber 5 of the enlarged portion 4 of the casing and the ring 19 expanded into the slot 21. The balls 8 will then be placed in the 45 chamber of the lower step-bearing and the latter screwed upwardly from the lower end of the casing until the balls engage the beveled lower end 9 of the spindle blade 10.

The step-bearing 7 may be conveniently 50 rotated by introducing the blade of a screw-driver into the slot or groove 21. When the step-bearing has been screwed up into the lower end of the casing sufficiently to properly adjust both the upper and lower bearings, it may be sealed by pouring a mass of 55 soft metal or other sealing material 23 into the lower end of the body of the casing. In order then to readjust or dismantle the 60 construction it would be necessary to remove the sealing material 23, unscrew or retract the lower step-bearing 7 until the spindle has dropped sufficiently to permit the cup member 12 to be depressed enough so that 65 the ring 19 can be pried out of its groove

18, whereupon the spindle and upper bearing may be removed through the upper end of the casing.

The chamber 5 provides an oil reservoir 70 which will maintain the bearing in a proper state of lubrication, oil being introduced through a suitable aperture in the wall of the casing which may be closed by a cap 24.

When a spindle becomes disabled, and sometimes for other reasons, it is desirable 75 to stop the rotation of the spindle without removing the same from its supporting frame and in accomplishing this purpose the band is slipped from the pulley of the whirl. In order to prevent the jumping of 80 the band when thus disengaged from the pulley of the whirl I have provided a groove 25 in the extension of the whirl above its pulley in which the band may rest or run idly. This groove will prevent the 85 jumping of the band and consequent jerking of the spindle.

It will be understood that the embodiment of the invention disclosed herein is 90 illustrative and not restrictive and that various other modifications may be made within the spirit and scope of the following claims.

Having fully described my invention, 95 what I claim as new and desire to secure by Letters Patent, is:

1. A ball-bearing spindle comprising a casing having a chambered upper end and an open lower end, a spindle blade, a step-bearing for said spindle adjustably secured 10 in the lower end of said casing, an upper ball-bearing in said chambered portion, and means for securing said upper bearing from removal from said chamber, unless the step-bearing is retracted.

2. A ball-bearing spindle comprising a casing having a cylindrical chamber at its upper end and an open lower end, a spindle blade, a step-bearing for said spindle adjustably secured in the lower end of said 11 casing, an upper ball-bearing for said spindle comprising a cone on said spindle blade, and a coöperating ball-retaining cup in said cylindrical chamber, and means for securing said cup in said chamber against 11 removal, unless the step-bearing is retracted.

3. A ball-bearing spindle comprising a casing having a cylindrical chamber at its upper end and an open lower end, a spindle blade, a step-bearing for said spindle adjustably secured in the lower end of said 1 casing, an upper ball-bearing for said spindle comprising a cone on said spindle blade, and a coöperating ball-retaining cup fitting the cylindrical walls of said chamber and 1 having a beveled upper edge and circumferential groove in the upper portion of the wall of said chamber, and a ring removably seated in said groove adapted to be engaged by said beveled edge, whereby the said bear- 1

ing cup cannot be removed, unless the step-bearing is retracted.

4. A ball-bearing spindle comprising a casing having a cylindrical chamber at its upper end and an open lower end, a spindle blade, a step-bearing for said spindle adjustably secured in the lower end of said casing, an upper ball-bearing for said spindle comprising a cone on said spindle blade, and a coöperating ball-retaining cup having a creeping fit with the cylindrical wall of said chamber, and means for retaining said cup in said chamber, unless the step-bearing is retracted.

15 5. A ball-bearing spindle comprising a casing having an enlarged upper end presenting a bearing chamber and an open lower end, a spindle blade, a ball-bearing for said spindle blade within said chamber, an 20 adjustable lower step-bearing in said casing having on its under side a transverse groove provided with undercut walls adapted to receive and support a sealing material, whereby tampering with the proper adjustment of 25 the bearing may be prevented.

6. A ball-bearing spindle comprising a casing having a body provided with exterior screw threads and an enlarged upper end, a spindle blade, a step-bearing for said spindle having a screw threaded periphery en-

gaging complementary screw threads in the inner wall of said casing, a transverse slot having an undercut wall in the outer face of said step-bearing adapted to receive a sealing material, an upper ball-bearing within 35 said chambered upper end, and means for securing said upper ball-bearing from removal from said chamber, unless the step-bearing is retracted.

7. A spindle comprising a casing, a spindle blade mounted therein, bearings for said spindle blade, means for relatively adjusting said bearings and means for sealing said bearings in place.

8. A spindle comprising a casing, a spindle blade mounted therein, upper and lower thrust bearings for said spindle blade, means for adjusting said lower thrust bearing and means for sealing said bearing in adjusted position.

9. A spindle comprising a casing, a spindle blade mounted therein, a thrust bearing for the lower end of said spindle blade, an upper ball bearing and means including an expandible member for securing the upper 55 ball bearing from removal.

In testimony whereof, I have signed my name to this specification.

THEODORE M. PRUDDEN.
